DESIGN FOR A COMBINED LAPEL WATCH AND REFLECTOR BUTTON

Alfred Benjamin Shawl, New York, N. Y.

Application March 30, 1942, Serial No. 106,383

Term of patent 3½ years

To all whom it may concern:

Be it known that I, Alfred Benjamin Shawl, a citizen of no country, residing at 110 West 47th St., New York, in the county of New York and State of New York, have invented a new, original, and ornamental Design for a Combined Lapel Watch and Reflector Button, of which the following is a specification, reference being had to the accompanying drawing, forming part thereof.

In the drawing

Fig. 1 is a front view of a combined lapel watch and reflector button, showing my new design.

Fig. 2 is front view showing the watch reversed and the reflector button in front.

Fig. 3 is a side view of the design.

The pendant element is pivotally mounted and the facial features are luminescent.

I claim:

The ornamental design for a combined lapel watch and reflector button, as shown and described.

ALFRED BENJAMIN SHAWL.
